UNITED STATES PATENT OFFICE.

HAROLD D. WATERHOUSE, OF QUINCY, MASSACHUSETTS, ASSIGNOR TO UNITED STORE SERVICE AND TUBE COMPANY, OF BOSTON, MASSACHUSETTS, A CORPORATION OF MAINE.

RECEIVING APPARATUS FOR PNEUMATIC-DESPATCH SYSTEMS.

No. 906,342.

Specification of Letters Patent.

Patented Dec. 8, 1908.

Application filed October 23, 1907. Serial No. 398,712.

To all whom it may concern:

Be it known that I, HAROLD D. WATERHOUSE, citizen of the United States, residing at Norfolk Downs, Quincy, in the county of 5 Norfolk and State of Massachusetts, have invented certain new and useful Improvements in Receiving Apparatus for Pneumatic-Despatch Systems; and I do hereby declare the following to be a full, clear, and exact description of the invention, such as will enable others skilled in the art to which it appertains to make and use the same.

The invention relates to receiving apparatus for pneumatic despatch systems, and 15 more especially to receiving apparatus such as is used for receiving comparatively large carriers at sub-stations.

The apparatus in which the invention is embodied comprises a cushioning chamber 20 arranged in line with or adapted to be brought into alignment with a transmitting tube and provided with two valves or gates, the inner valve being normally open and the outer valve normally closed. When the carrier enters the cushioning chamber the air between the carrier and outer valve is compressed and forms an air cushion for stopping the carrier. The compression of the air between the carrier and the outer valve sets 25 mechanism into operation which closes the inner valve and opens the outer valve, and also admits compressed air to the cushioning chamber back of the carrier so that the carrier is delivered from the chamber onto the receiving table or pan. The delivery of the carrier causes the valves and operating mechanism to return to normal position ready for the reception of another carrier.

The invention relates to mechanism for operating and controlling the valves, and consists in the combinations and features herein-after described and set forth in the claims.

The invention will be understood from an inspection of the accompanying drawing, in 45 which—

Figure 1 is a vertical sectional view of an apparatus embodying the invention, and Figs. 2, 3 and 4 are details of certain valves to be described.

50 In the apparatus illustrated the carrier or transmission tube A² is connected through a bypass A with a tube A³ through which the compressed air within the carrier tube passes

after the carrier has passed beyond the bypass A. A cushioning chamber C is arranged 55 in line with the carrier tube and communicates therewith through a tube B. The communication between the cushioning chamber and carrier tube is controlled by a gate valve D which is connected to a piston S mounted 60 in a cylinder R. The outer end of the cushioning chamber communicates through a pipe B² with the atmosphere, and the carrier passing through the cushioning chamber passes through the tube B² and is delivered onto a 65 receiving pan or table D'. The communication between the cushioning chamber and the delivery tube B² is controlled by a gate or valve E which is connected to a piston U mounted in a cylinder T. The upper ends of 70 the cylinders R and T are in free communication with the atmosphere through pipes R' and T' respectively, so that the pistons S and U will fall to the bottom of the cylinders R and T when the lower ends of the cylinders 75 are opened to the atmosphere.

The pistons S and U are normally at the lower ends of the cylinders R and T, and when in this position the valve D is open and the valve E closed. Compressed air is supplied to the lower end of the cylinders R and T to raise the pistons and thus close the valve D and open the valve E through a pipe L and branch pipes N and O. The flow of air through the branch pipe N leading to the 80 bottom of the cylinder R is controlled by a check valve V arranged to allow the passage of air to the cylinder, but to prevent the passage of air from the cylinder unless the valve is held open. When the parts are in normal 85 position the valve V is held open by means of a bell crank lever F', one arm of which acts upon a pin F² which raises the valve V, and the other arm of which is connected by a link W with a second bell crank lever Y. The 90 bell crank lever Y is forced in a direction to disengage the lever F' from the pin F² by a spring E'. The lever Y is held in a position to hold the valve V open by a pin X which is engaged by the piston U when said piston is 95 at the lower end of the cylinder T.

The passage of air through the branch pipe O to or from the lower end of the cylinder T is controlled by a valve P which is held normally closed by a spring P'. The stem of 100 105 the valve P is connected with a diaphragm

P² arranged in a casing P³ and held in its upper position by the spring P'. The chamber above the diaphragm is connected through a pipe Q' with a port Q formed near the upper end of the cylinder R. When compressed air is admitted to the cylinder R and moves the piston S to the upper end of the cylinder, the piston passes the port Q, which is thus brought into communication with the compressed air within the lower part of the cylinder, and this air passing through the pipe Q' operates the diaphragm P² and opens the valve P.

The supply and exhaust of air through the pipe L is controlled by a valve K which is normally in such position that the port at the end of the pipe L is open to the atmosphere. When the valve K is moved toward the left it opens communication between the port at the end of the pipe L and a port at the end of a pipe M the other end of which is in communication with the transmission tube. The valve K is operated by a piston J mounted in a cylinder H, one end of which is connected with the supply pipe M through a branch pipe M' and the other end of which is connected through a pipe G' and check valve G with a chamber G² which is in communication with the outer end of the cushioning chamber through a port F. The pipe G' also connects through a branch pipe G³ with a valve chamber I'. The valve chamber I' is normally closed by an exhaust valve I which is held to its seat by a spring I² and is connected with a diaphragm C'. The chamber above the diaphragm C' is connected through a port B' with the pipe B² and when pressure is transmitted through this port to the diaphragm the valve I is operated to open communication between the pipes G² G' and the atmosphere so that the pressure in said pipes is relieved.

When a carrier is discharged from the carrier or transmission tube it passes through the tube B into the cushioning chamber where it is brought to rest by reason of the compression of the air between the carrier and the valve E. A part of the air compressed between the carrier and valve E passes through port F, chamber G², check valve G, and pipe G' into the end of the cylinder H, and forces the piston J toward the left against the pressure transmitted from the carrier tube through the pipes M M'. This movement of the piston shifts the valve K to the left, opening communication between the supply pipe M and the pipe L, and the valve is held in position by the air entrapped in the pipes G' G² and cylinder H. Compressed air now flows through the pipe L and branch pipe N to the lower end of the cylinder R, the valve V being open at this time and the valve P in the branch pipe O being closed to prevent the passage of air to the lower end of cylinder T. The air thus

supplied to the lower end of the cylinder R raises the piston S, thus closing the inner valve D. As the piston S reaches the upper end of the cylinder R it passes the port Q and compressed air is supplied through this port and the pipe Q' to the chamber above the diaphragm P', so that this diaphragm is depressed, opening the valve P and allowing compressed air to flow through the pipe O to the lower end of cylinder T. This air acts to raise the piston U, thus opening the valve E, and bringing the opening Z which is formed in the valve plate into register with the tube B' and cushioning chamber. The upward movement of the piston U frees the pin X and lever Y, so that the lever F' is operated to release the check valve V, which closes and prevents the escape of air from the lower end of cylinder R until the valve is again opened. After the valve D is thus closed and the valve E opened, air is admitted back of the carrier through a port A' formed in the valve D, and this air forces the carrier out through the tube B' so that it is delivered onto the receiving pan D'. After the rear end of the carrier has passed the port B' the pressure back of the carrier is transmitted through the port B' to the diaphragm C', forcing said diaphragm down against the tension of the spring I² and opening the exhaust valve I. This relieves the pressure in the pipe G' and right-hand end of the cylinder H so that the pressure supplied through the pipe M' moves the piston J to the right. This movement of the piston shifts the valve K to the right, cutting off the communication between the supply pipe M and the pipe L, and opening the pipe L to the atmosphere. At this time the valve P is still held open by the compressed air entrapped within the cylinder R below the piston S and the pressure within the lower end of the cylinder T is relieved, allowing the piston U to fall to the lower end of the cylinder by gravity, thus closing the valve E. As the piston U reaches the lower end of the cylinder T it strikes the pin X and operates the bell crank levers Y and F' to open the valve V and thus relieve the pressure in the lower end of the cylinder R. The piston S now falls by gravity to the lower end of the cylinder, thus opening the inner valve D. At the same time the port Q is opened to the atmosphere through the cylinder R and pipe R', and the valve P is closed by the action of the spring P'. As soon as the carrier is delivered the port B' is opened to the atmosphere, and the exhaust valve I is closed by the spring I². The parts are now all in normal position, ready for the reception of another carrier.

By operating and controlling the valves in substantially the manner described, the proper timing of the parts is insured, and the valves are operated in a reliable and effective manner with a minimum amount of 125 130

compressed air, and the controlling of the parts is effected without requiring the presence of devices extending into the path of the carrier which are liable to cause injury to or 5 undue wear upon the carrier and apparatus.

Having set forth the nature and object of the invention, and specifically described one form of apparatus in which it may be embodied, what I claim is:—

- 10 1. A receiving apparatus for pneumatic despatch systems, having, in combination, a cushioning chamber, a valve normally closing the same, a piston connected with the valve, a cylinder within which the piston is 15 mounted having its upper end open to the atmosphere, an air supply for the cylinder, a valve for controlling the air supply, means for operating the controlling valve by air compressed by the carrier and entrapping 20 said air to hold the valve, and means for venting said entrapped air to return the controlling valve to normal position and vent the cylinder to allow the return of the piston to the lower end of the cylinder, substantially 25 as described.

2. A receiving apparatus for pneumatic despatch systems, having, in combination, a cushioning chamber, a valve normally closing the same, a piston connected with the 30 valve, a cylinder within which the piston is mounted, an air supply for the cylinder, a valve for controlling the air supply, means for operating the controlling valve by air compressed by the carrier, a second valve for 35 controlling the flow of air to and from the cylinder, an inner valve for the cushioning chamber, and means for controlling the opening and closing of said second valve by the operation of the said inner valve, substantially 40 as described.

3. A receiving apparatus for pneumatic despatch systems, having, in combination, an air cushioning chamber, a normally open inner and a normally closed outer valve for 45 the chamber, pistons connected with the valves, cylinders within which the pistons are mounted open to the atmosphere at their upper ends, an air supply, means operated by the entrance of a carrier to connect the 50 lower end of the inner cylinder with the air supply, means rendered operative by the closing of the inner valve to connect the outer cylinder with the air supply, means for discharging the carrier, means operated by 55 the discharge of the carrier to disconnect the cylinders from the air supply and vent the outer cylinder, and means operated by the closing of the outer valve to vent the inner cylinder, substantially as described.

- 60 4. A receiving apparatus for pneumatic despatch systems, having, in combination, an air cushioning chamber, a normally open inner and a normally closed outer valve for the chamber, an air supply for operating the 65 valves, a valve for controlling the air supply,

means for forcing said valve yieldingly in one direction, means for operating said valve in the opposite direction by air compressed between the carrier and the outer valve and entrapping said air to hold the valve, and 70 means out of the path of and operated by the discharge of the carrier to vent said entrapped air, substantially as described.

5. A receiving apparatus for pneumatic despatch systems, having, in combination, 75 an air cushioning chamber, a normally open inner and a normally closed outer valve for the chamber, pistons connected to the valves, cylinders within which the pistons are mounted open to the atmosphere at their 80 upper ends, an air supply, a valve for controlling the connections between the air supply and lower ends of the cylinders, means for operating said controlling valve in one direction by air compressed by the carrier 85 and entrapping said air to hold the valve and means operated by the pressure back of the carrier after it has passed the outer valve to vent said entrapped air, substantially as described.

90 6. A receiving apparatus for pneumatic despatch systems, having, in combination, a cushioning chamber, a normally open inner and a normally closed outer valve for the chamber, a piston connected to the inner 95 valve, a cylinder in which the piston is mounted having one end open to the atmosphere, means operated by the entrance of a carrier into the cushioning chamber for admitting compressed air to the other end of 100 the cylinder of the inner valve to close the valve, and means operated by the closing of the outer valve for allowing the escape of said air, substantially as described.

7. A receiving apparatus for pneumatic 105 despatch systems, having, in combination, a cushioning chamber, a normally open inner and normally closed outer valve for the chamber, a piston connected to the inner valve, a cylinder in which the piston is 110 mounted having one end open to the atmosphere during the opening and closing of the connected valve, a valve through which compressed air is admitted to the end of the cylinder, and means for opening said valve to 115 vent the cylinder by the closing of the outer valve, substantially as described.

8. A receiving apparatus for pneumatic despatch systems, having, in combination, a cushioning chamber, a normally open inner 120 and normally closed outer valve for the chamber, a piston connected to the inner valve, a cylinder in which the piston is mounted open to the atmosphere at its upper end, a supply pipe connected with the lower end of the cylinder, a valve in the pipe for preventing back flow of air, means operated by the entrance of the carrier for connecting said supply pipe with an air supply, means operated by the discharge of the carrier for 125 130

venting the supply pipe, and means for opening the valve in the pipe by the closing of the outer valve, substantially as described.

9. A receiving apparatus for pneumatic despatch systems, having, in combination, a cushioning chamber, a normally open inner and normally closed outer valve for the chamber, an air supply, a valve for controlling the connections between the air supply and the valves, a piston connected with said controlling valve, a conduit leading from the outer end of the cushioning chamber to one side of said piston, a check valve in said conduit for preventing back flow of air, a normally closed exhaust valve through which said conduit is vented, a diaphragm connected to said valve, and a port beyond the outer valve leading to one side of the diaphragm, substantially as described.

10. A receiving apparatus for pneumatic despatch systems, having, in combination, a cushioning chamber, a normally open inner and normally closed outer valve for the chamber, pistons connected to the valves, cylinders within which said pistons are mounted open to the atmosphere at their upper ends, supply pipes leading to the lower ends of the cylinders, a valve operated by the entrance of a carrier for controlling the connection between said pipes and an air supply, valves in the pipes for controlling the flow of air to and from the cylinders, means for controlling the valve in the supply pipe for the outer cylinder by the closing and opening of the inner valve, and means for controlling the valve in the supply pipe for the inner cylinder through the opening and closing of the outer valve, substantially as described.

11. A receiving apparatus for pneumatic despatch systems, having, in combination, a cushioning chamber, a valve normally closing the same, an air supply for operating the valve, a valve for controlling the air supply, means for operating the controlling valve by air compressed by the carrier and entrapping said air to hold the valve, and means out of the path of the carrier for venting said entrapped air to return the controlling valve to normal position, substantially as described.

12. A receiving apparatus for pneumatic despatch systems, having, in combination, a cushioning chamber, a valve normally closing

the same, a piston connected with the valve, a cylinder within which the piston is mounted, an air supply for the cylinder, a valve for controlling the communication between the cylinder and air supply, means for normally holding the valve in position to cut off communication between the cylinder and air supply, means for operating the controlling valve by air compressed by the carrier and entrapping said air to hold the valve, and means for venting the said entrapped air to return the controlling valve to normal position, substantially as described.

13. A receiving apparatus for pneumatic despatch systems, having, in combination, a cushioning chamber, an inner and outer valve for the chamber, pistons connected with the valves, cylinders within which the pistons are mounted, open to the atmosphere at their upper ends, an air supply, means operated by the entrance of the carrier to connect the lower end of the inner cylinder with the air supply, means operated by the closing of the inner valve to connect the outer cylinder with the air supply, means for disconnecting the cylinders from the air supply and venting the outer cylinder, and means operated by the closing of the outer valve to vent the inner cylinder, substantially as described.

14. A receiving apparatus for pneumatic despatch systems, having, in combination, a cushioning chamber, inner and outer valves for the chamber, a piston connected with the inner valve, a cylinder in which the piston is mounted open to the atmosphere at its upper end, a supply pipe connected with the lower end of the cylinder, a valve in the pipe for controlling the flow of air therethrough, means operated by the entrance of the carrier for connecting said supply pipe with an air supply, means for connecting the supply pipe with the atmosphere after the outer valve has opened, and means for opening the valve in the supply pipe by the closing of the outer valve, substantially as described.

In testimony whereof I affix my signature, in presence of two witnesses.

HAROLD D. WATERHOUSE.
